[57] CLAIM

The ornamental design for a photo control with interior
plug-type terminals, as shown.

DESCRIPTION

FIG. 1 is a front elevational view of a photo control
with interior plug-type terminals showing my new de-
sign;

FIG. 2 is a right side elevational view thereof, the left
side elevational view being a mirror image;

FIG. 3 is a top plan view thereof, the bottom plan view
being a mirror image;

FIG. 4 is a rear elevational view thereof; and

FIG. 5 is a perspective view thereof on an enlarged
scale.

FIG. 1

FIG. 2

FIG. 3

FIG. 4

FIG. 5
